UNITED STATES PATENT OFFICE.

EUGENE M. DEILLER, OF IRVINGTON, NEW JERSEY.

TOBACCO STRIPPING AND BOOKING MACHINE.

Application filed June 29, 1920. Serial No. 392,622.

To all whom it may concern:

Be it known that I, EUGENE M. DEILLER, a citizen of the United States, and a resident of Irvington, in the county of Essex and 5 State of New Jersey, have invented new and useful Improvements in Tobacco Stripping and Booking Machines, of which the following is a specification.

This invention relates to tobacco stripping and booking machines of that type set forth in the United States Patent No. 1,287,906 of December 17, 1918.

The objects of the invention are to secure a tobacco stripper which strips the stems of 10 a tobacco leaf clean and without breaking the same, even at the small or tip end; to provide for this purpose mechanism which guides the leaf so as to keep the stem in proper alignment; to avoid tearing of the 15 leaves or halves of leaves, especially by entanglement in the machine; to thus provide a machine which conserves and economizes material; to perform the stripping in advance of the booking; or strip a considerable 20 portion of the length of the leaf before it is caught between the drum and belts; to provide improved means for mounting the presser roller for smoothing the leaves before they enter the cutter; to provide an 25 improved spring means for maintaining the presser roll under proper pressure; to secure a simple and compact construction which 30 will produce satisfactory results even in the hands of an inexperienced operator, and secure 35 other advantages and results as may be brought out in the following description.

Referring to the accompanying drawings in which like numerals of reference indicate the same parts throughout the several views,

40 Figure 1 is an elevation of the improved machine from the front where the operator sits;

45 Figure 2 is an elevation of the machine looking at its left-hand side, or side at the operator's left-hand.

Figure 3 is a transverse vertical sectional view taken on the line 3—3 of Fig. 1, portions being broken away;

50 Figure 4 is an elevation of the machine looking at the right-hand side, or side at the operator's right-hand, portions being broken away;

Figures 5 and 6 are views of the clutch

operating mechanism taken on the line 5—6 of Fig. 1, and looking in the direction of the 55 arrow, said figures showing respectively, the position of the parts when the clutch is thrown out and when it is thrown in;

Figure 7 is a detail perspective view of the control trip with its slide removed; 60

Figure 8 is a top edge view of said slide;

Figure 9 is a detail view of the knives and 65 knife shaft, partly in longitudinal section;

Figure 10 is a similar view of the brush and brush shaft; 65

Figure 11 is a detail top plan view of the pressure roll mounting; and

Figure 12 is a detail perspective view of the leaf deflector and cleaner for the cutter. 70

In the specific embodiment of the invention shown in said drawings, 1, 2 indicate suitable side pieces or frames connected by tie-rods 3, 4 and struts or braces 5, 6. Between the upper parts of said side frames 1, 2 is mounted a drum, comprising end 75 sections 7, 7, made fast upon a shaft 8, as by set screws 9, in spaced relation to each other, the space between said drum sections 7, 7 being substantially the width of the cut to be made in removing the stems of the 80 tobacco leaves to be stripped. Between the adjacent ends of said drum sections 7, 7 is a circumferential projecting flange 10, preferably closing the space between the drum sections and preferably having an annular 85 groove 11 on its periphery to receive the stem of a leaf.

At the front of the machine and preferably mounted upon an axis slightly below that of the drum, is a cutter roller 12 comprising end sections 13, 13 which cooperate with the sections 14, 14 of a cutter to remove the stems from the leaves. Around these roller sections 13, 13 extend a plurality of belts 15 which pass rearwardly over said roller sections and then beneath the drum, lying against said drum for the greater part of its circumference and leaving it at an upper point of the front side of the drum or same side at which they entered beneath it. 90

As shown in the drawings, the circumferential points at which the belts enter beneath the drum and leave the same are spaced apart sufficiently to allow free access to the drum to remove the booked leaves, and the 105 axis of the cutter roll 12 is disposed above

the horizontal diametric plane of the drum so as to position the point of contact of the leaves with the drum below the cutters, thus causing the leaf issuing from the cutters to follow the belts downwardly to the drum and be gripped therebetween without bending, wrinkling or folding of the leaves, and preventing the tendency of the leaves to turn upwardly. Where the belts leave the drum they turn backward and upward around a roller 16, and then they extend over a forward top roller 17, a rear top roller 18, individual tension rollers 19 at some distance below the drum, and extend upwardly forward over a small lower front roller 20 adjacent the cutter roll and adapted to guide the belts beneath the same to extend upward in front of it, all as clearly shown in Figure 3 of the drawings.

20 A driving shaft 21 is mounted in the side frames preferably below the drum sections 7, 7, and extends at one end beyond the side frame and carries a driving pulley 22 adapted to receive a belt 23 driven from a pulley 24 mounted on a countershaft 25 journaled in a suitable bearing 26 fastened to the rear of the side piece 2 of the machine frame, the said countershaft 25 receiving power through a pulley 27 and belt 28 from a conventional motor 29 mounted on a bracket 30 at the top of the side piece 2 of the frame. At the other end, said shaft 21 projects beyond the side frame and carries a pinion 31 meshing with a gear wheel 32 keyed to the drum shaft 8, by means of which the drum is driven. The rear top roller 18 and cutter roller 12 are driven at the same rate of speed by means of gears 33 and 34 meshing with the gear wheel 32 and secured to the shaft 34 of the roller 18 and the shaft 35 upon which the cutter roll 12 is mounted, respectively. The rollers 18 and 12 and the drum are thus each positively driven at substantially the same peripheral speed so as to ensure proper breaking of the leaves and to prevent slipping of the belts 15.

50 The cutter roll sections 13, 13 are slidably mounted upon the shaft 35 and are adapted to be clamped in any position to which they are adjusted with respect to each other, by the set screws 36. It will be understood that these cutter roll sections 13, 13 are moved nearer together or further apart to accommodate the width of stem of the tobacco of different kinds, and at their adjacent ends the roll sections 13, 13 have disks 37, 37 which project beyond the roll sections and form annular cutting flanges preferably beveled from their outer sides somewhat bluntly inward as shown.

60 Above the cutter roll is arranged the cutter proper, comprising a shaft 38, see Figures 1 and 9, with knives 40, 40 which work between the flanges 37, 37 of the cutter roll

and are provided with hubs 41, 41 projecting away from each other and forming long bearings on the shaft 38. Said hubs each have a longitudinal slot 42 receiving a key 43 on the shaft 38, by means of which the hub and its knife rotates with the said shaft 70 and yet is slidable longitudinally thereof. Resilient means for normally holding said knives slid apart in frictional engagement with the cutting flanges 37, 37, and for regulating the resilient tension, is provided in 75 the following structure. A helical spring 44 on the shaft 38 is connected to the end of each hub away from its knife and also connected at its other end to a collar 45 made fast on the shaft 38, as by a set screw 46, these springs being under tension so as to draw the two knives apart and cause them to press against the inner sides of the cutter roll flanges 37, 37. The knives are each formed with the face next the hub offset somewhat inwardly over the hub around the periphery as at 47 leaving an undercut 48 in the blade around the hub. Furthermore, the hub is reduced in diameter at its end next the blade as at 49 forming a peripheral groove. As the stem is sheared from the leaf, the fresh cut edge of the leaf is thus afforded room to be pressed downward past the peripheral cutting edge 47 without being in constant frictional contact at its edge with the knife and hub and therefore not curled or retarded thereby. A bushing 50 is fitted loosely on the shaft 38 and extends between the keys 43 across the space between the knives 40 so as to 100 form a guard for a cleaning implement which may be inserted between the knives to clean the same and prevent the cleaning implement from being caught in the keyway in the shaft.

105 The cutter is driven by means of a gear 51 secured to the cutter shaft 38 and meshing with a gear 52 on the cutter roller shaft 35 arranged adjacent the gear 34 through which the cutter roller 12 is driven. The knives 40 being held in frictional engagement with the cutter roller flanges 37 and rotated simultaneously therewith, will not only cut the tobacco with a sharp true cut, but will discharge the stems freely and exert no tendency to entangle said stems.

110 The stem of tobacco leaf is fed in between the flanges 37, 37 of the cutter roll with either end first, and the side portions of the leaf are spread out upon the roller sections 13, 13 and the belts 15 thereon. In order to support the stem a rest 53 is inserted between the roller sections 13, 13 comprising a light bar projecting upward from a bracket 54 secured to the front frame strut 5, see Figure 3, said bar curving inwardly over the cutter roller shaft 35 with its inner end extending substantially par-

allel to the belts 15 and a little below the same, the said inner end of the rest being tapered away from the flanges 37 of the cutter roll to prevent sticking of the stems and juice between the rest and flanges 37. The rest 53 is preferably removably and adjustably supported in the bracket 54 by means of a screw 55 adapted to engage any one of a series of openings 56 in the foot of the 10 rest to hold the rest in a vertical recess or groove 57 in the bracket 54. The elevation of the rest 53 is thus adjustable for various sizes of stems, and it can be removed for cleaning or replacing. For guiding the 15 stems away from the rest 53, a discharge chute 58 is secured to the bracket 54 and extends downwardly beneath the drum to guide the stems away from the drum and belts to prevent entanglement. It will be 20 noted that the two belts 15 adjacent the chute 58 on opposite sides thereof are twisted between the rollers 20 and the tension rollers 19 so as to provide clearance for the falling stems.

25 An idle presser roller 59 is preferably arranged above the cutter roll and in front of the cutter as shown in Figures 3 and 12 especially. This roller 59 is mounted at its ends on conical bearing points 60 at the 30 outer ends of bracket arms 61 integral with collars 62 loosely mounted on the cutter shaft 38, said roller being yieldingly held against the cutter roller 12 by means of an inverted U-shaped leaf spring 63 interposed 35 between a rod 61^a extending between the bracket arms 61 and a bar 64 extending across the front of the machine above the roller 59 and fastened to the side frames 1 and 2. The spring 63 will yield to accommodate inequalities or rough spots in the leaves but will hold the rollers 59 against the leaves to smooth and guide them. The roller is grooved at its center, as at 59^a, to clear the flanges 37, 37 of the cutter roller 40 and direct the leaf stem over the knives.

45 It will be noted that the stem of a leaf is entirely cut out before the leaf enters between the drum and belts, and it is the purpose of my invention to allow sufficient distance between the cutter and drum so that the stem will assume its proper course before the side portions of the leaf become clamped between the drum and belts. The pressure of the idle roller 59 is light and not sufficient 50 to hold the side portions of the leaf so that the stem cannot assume its proper position and direction upon entering the machine. The stem is compelled to take its proper 55 course by the support 53 and cutting flanges 55 and the side portions of the leaf follow it; the stem is thus cut out of the leaf by means which follows the stem and will shift the position of the leaf portions before it will cut 60 across the stem. As the severed stem passes

down the inner portion of the support 53 65 between the cutting flanges it guides the leaf portions on either side of itself down the belts 15 and between the same and the drum sections so that successive leaf portions are accurately and exactly booked.

70 The roller 16 at the front of the drum over which the belts turn backward, is mounted in an apron consisting of end arms 65, 65 having their rear ends made fast on the shaft 66 of the top front roller 17. The shaft 67 of the roller 16 has its bearings in the forward ends of the arms 65, 65, and a brush shaft 68 is also journaled in the outer ends of said arms in front of the roller 16, 75 said brush shaft being driven by a pinion 69 on the brush shaft which normally meshes with the gear wheel 32. Said brush shaft comprises end portions 70, 70 journaled in the arms 65, 65 and carrying between themselves the twisted wire 71 which is provided 80 with radially projecting bristles as is common in brush making, said twisted wire being in alignment with the shaft portions 70, 70 and shown inserted within and secured to suitable sleeves 72 which are inserted in 85 holes in the ends of the shaft portions, although any other suitably equivalent construction could be employed. The sleeve 72 at the end of the brush next the pinion 69 is fixed to the shaft portion as by a set 90 screw 73 so that the brush will be rotated as the gear rotates. The other sleeve may rotate within the shaft portion 70 providing a long bearing. The brush is thus between 95 the arms 65, 65 of the apron and is positioned with reference to the roller 16 so as to engage the same and brush it and the belts thereon sufficiently to disengage therefrom the ends of any leaves or halves of leaves which tend to leave their booked position and follow the belts 15 around the roller 16 because of adhesion or the like.

100 It will be noted that the brush just described is exposed toward the front of the machine, so that if any leaf or portion of a leaf escapes in spite of said brush it will be readily accessible to the operator and can be removed without injury or entanglement in the machine, and again fed into the machine and booked.

105 To positively disengage any portions of the leaves which might stick to the cutter and to clean the hubs 41 of the cutter and knives 40 of any portions of the leaves, dirt or gum, a cleaning plate 74 is secured substantially centrally of the bar 64 extending across the front of the machine, said cleaning plate having one end bifurcated at 75 and returned upon itself at 76 to clip around the bar 64 and a keeper 77 secured to the bar to prevent longitudinal movement of the plate on the bar. The other end of the cleaning plate 74 bears yieldingly against the up-

per surface of the hubs 41 of the cutter and is notched at 78 to clear the knives 40 on the cutter, the said notch being of sufficient width to allow the knives 40 to be spread by the springs 44. A moistening pad 79 is fitted beneath the plate 74 to moisten and clean the presser roller 59 and knives 40, said pad being loose and held in engagement with the said knives and roller by the plate 10 74.

The apron which carries the roller 16 and brush as described is adapted to be swung upward from its solid line position to the dotted line position shown in Figure 3 of the drawing, in order to expose the ends of booked leaves on the drum and enable the books to be removed or grasped for removal, and for this purpose I have shown the end of the shaft 66 upon which the apron 15 is secured as provided with a handle 81, see Figures 1 and 4. This handle has a hub which is clamped upon the shaft 66 by a set screw or otherwise made fast thereon.

Each of the side arms 65 of the apron is 25 provided with an outwardly extending lug 82 which carries an adjustable stop screw 83 adapted to engage an abutment 84 on the corresponding side frame of the machine. By adjustment of these screws 83, the extent of the downward movement of the apron can be varied to provide proper meshing of the pinion 69 on the brush shaft 68 with the gear wheel 32. The screws 83, once 30 adjusted, thus serve as stops for the apron so that no particular care is necessary in 35 lowering the apron to cause proper operation of the brush or roller 16. To limit the upward and backward movement of the apron stop arms 85 are secured to or made 40 integral with the sides of the frame and are provided with adjustable stop screws 85^a against which the arms 65 of the apron are adapted to rest.

The individual tension rollers 19 are each 45 mounted in an arm 86 which is pivoted on the rear tie-rod 3 and preferably extends forward and downward therefrom. Tension upon each belt is secured by attaching to the arm 86 intermediate the roller 19 and tie-rod 3 a helical spring 87 which extends 50 rearward and is connected at its other end to an eye 87^a secured in the strut 6 of the frame. It will be noted that the arms 86 with their tension roll 19 and tension springs 55 87 lie wholly within the lower part of the frame work of my improved machine so as to be guarded and shielded thereby against impact and injury from anything passing the machine.

60 In order to enable the drum to stop at the end of each complete rotation, for the insertion of a new leaf, and to enable it to be stopped and started at any time by the operator, the pulley 22 is provided with a clutch

having a sliding collar 88 adapted to be 65 operated by a lever 89 fulcrumed intermediate its ends upon a bracket 90 projecting from the side frame 2, said lever being adapted to swing in a horizontal plane as 70 shown, although of course this is not essential. Any suitable and well-known form of clutch may be employed, but I prefer to use, and have shown, the clutch set forth in the United States Patent of Martin Deiller, No. 1,176,438 of March 21, 1916, and to which 75 reference may be had for further description of said clutch if desired.

The forward end of the lever 89 or end 80 away from the clutch lies in the fork of the upright arm 91 of a bell-crank lever pivoted upon a bracket 92, see Figure 1, to swing in a plane transverse to the lever and having its other arm 93 projecting horizontally through the side frame 2. At the free or inner end of this arm 93 is a pin 94 projecting toward the back of the machine and normally at the upper end of a slot 95 in a link 96 which extends upward to a trip 97 pivoted as at 98 upon the inner side of the frame 2 and adapted to swing up and down 90 to work the bell-crank lever and throw the clutch in and out. A spiral spring 99 normally holds said trip at its upper limit of movement and holds the link upward so the bell-crank lever arm 93 may swing upward and allow the clutch to be thrown in under the action of a spring 100 forming part of the clutch mechanism. This trip 97 provides at 95 its inner side a slideway 101 for a slide 102, said slide having at one end a portion 103 projecting from the trip far enough to engage a pin 104 on the end of the drum, which pin will however clear the trip itself. Obviously if the slide 102 is in proper position the pin 104 will engage the projection 103 and depress the trip 97 to throw out the clutch and stop the drum. In this way the 100 drum is automatically stopped at the end of each rotation, for the insertion of a new leaf.

In order to start the drum rotating means are provided for sliding the slide 102 to withdraw its projection 103 from beneath the drum pin 104, whereupon the spring 99 will draw the trip upward and allow the clutch to be thrown in. Any suitable means could be employed such as a slide releasing bell-crank 105 pivoted upon the inner side of the frame 2 with one arm extending upwardly and connected to the slide by a slot-and-pin and its other arm connected by a rod 106 to a treadle 107 mounted upon the front bottom tie-rod 4, said treadle being normally held upward to throw the slide 102 into position to be engaged by the pin 104 and stop the drum. A stop 108 projecting from the side piece 2 in the path of 110 swing of the bell-crank 105 in proper posi- 115 120 125

tion to limit the outward swing thereof and prevent the slide 96 from too great movement outward. Also a stop or pin 109 projects from the slide 102 near its forward end toward the trip, and works in a groove 110 in said trip as the slide is moved back and forth, said groove being limited in length so that the stop will engage the end thereof and thus limit the retractive movement of the slide 96 when the treadle is depressed.

To enable the operator to stop the drum at any time during its rotation preferably a rod 111 is provided extending from the forward end of the lever 89 transversely of the machine through the side frame 2 and pivoted at its end to the upright arm of a bell-crank lever 112 which is fulcrumed upon a bracket secured to the side frame 2, as shown in Figure 1. The other arm of said bell-crank lever 112 is connected by a downwardly extending rod 113 to a foot treadle 114 also mounted upon the front bottom tie-rod 4 at the left-hand side of the machine and is normally held upward by a spring 115 with the clutch thrown in. Thus, by simply depressing the left-hand foot treadle 114, the operator can at any time stop the machine, while by depressing the right-hand treadle 101 he can start the machine when a new leaf is inserted, and since the bell-crank arm 93 is connected by slot and pin through the link 96 to the trip 97 the trip will not be disturbed by depressing the left-hand treadle 114 which swings said arm 93 in throwing the clutch out.

To prevent backward rotation or rebounding of the drum after its forward rotation has been stopped in the above manner, and thus prevent the clutch shoes from being thrown against the constantly rotating pulley 22, a stop lug 116 is secured to the periphery of the drum at one end thereof, said stop lug being adapted to be engaged by a gravity operated pawl or dog 117 pivoted on the upper tie rod 3, see Figure 3. The rear end of said lug 116 is slightly beveled so that the end of the dog 117 in dropping behind it will always be in tight engagement with the lug to take up lost motion, and this bevel also compensates for wear of the dog and lug. It is obvious that the lug can slip forwardly under the dog as the drum rotates in a forward direction, but that upon stopping of the drum by the stop mechanism above described the dog will fall behind the lug to prevent backward rotation of the drum. Unnecessary wear of the clutch shoes is thus avoided.

In some instances where the tobacco leaves are unusually gummy or moist, or the stems are unusually large, there would be a tendency for the severed stems to stick in the annular groove 61 on the drum, and to

eliminate this possibility a deflector plate 65 118 may be conveniently hingedly connected at one end, as at 119, to the drive shaft 21, the other end of the plate having a tongue 120 engaging the annular groove 11, and a spring 121 being connected between the plate 118 and the strut 6 at the rear of the machine to yieldingly hold the tongue 120 in the groove 11, (see Figure 3). If any stem sticks in the groove 11 after passing the chute 58 the tongue 120 will dislodge it, and cause it to fall beneath the machine. The deflector plate 118 also serves to deflect the stems toward the front of the machine to prevent the stems from piling up at the rear and entangling in the tension pulleys 19 and 80 belts 15.

Having thus described the invention, what I claim is:

1. In a machine of the character described, the combination with a drum, booking belts 85 extending around said drum, a cutter roller, a cutter shaft, a cutter on said shaft to cut out the stem of a leaf as it passes between the drum and belts, and drive means for said belt and cutter roller, of a pair of loose collars rotatable on said cutter shaft and each having a laterally projecting bracket bearing arm, and a presser roller journaled between said bracket arms and engaging the cutter roller to smooth out the leaves as they pass 95 into the cutter.

2. In a machine of the character described, the combination with a drum, booking belts 100 extending around said drum, a cutter roller, a cutter shaft, a cutter on said shaft to cut out the stem of a leaf as it passes between the drum and belts, and drive means for said belt and cutter roller, of a pair of loose collars rotatable on said cutter shaft and each 105 having a laterally projecting bracket bearing arm, a presser roller journaled between said bracket arms and engaging the cutter roller to smooth out the leaves as they pass into the cutter, and spring means for yieldingly maintaining said presser roller in engagement with the cutter roller.

3. In a machine of the character described, the combination with a drum, booking belts 115 extending around said drum, a cutter roller, a cutter shaft, a cutter on said shaft to cut out the stem of a leaf as it passes between the drum and belts, and drive means for said belt and cutter roller, of a pair of loose collars rotatable on said cutter shaft and each 120 having a laterally projecting bracket bearing arm, a presser roller journaled between said bracket arms and engaging the cutter roller to smooth out the leaves as they pass into the cutter, a rod connected between the bracket bearing arms, and spring means engaging 125 said rod to yieldingly maintain said presser roller in engagement with said cutter roller.

4. In a machine of the character described,

the combination with a frame, a drum rotatably mounted thereon, booking belts extending around said drum, means for driving said drum, means for cutting the stem 5 out of a leaf as it enters between the said drum and belts, and means for automatically stopping rotation of said drum, of means for preventing rebounding or backward ro-

tation of said drum after its forward rotation is stopped comprising a lug secured to 10 said drum, and a dog pivotally mounted on said frame to engage the rear of said lug as the drum is stopped, said dog allowing the lug to slip under it as the drum rotates forwardly.

EUGENE M. DEILLER.
